(57) CLAIM

I claim the ornamental design for a crescent hanger, as shown and described.

DESCRIPTION

FIG. 1 is a perspective view of a crescent hanger;
FIG. 2 is a right side view thereof;
FIG. 3 is a left side view thereof;
FIG. 4 is a front view thereof;
FIG. 5 is a rear view thereof;
FIG. 6 is a top view thereof;
FIG. 7 is a bottom view thereof;
FIG. 8 is a perspective view thereof, shown in an environment of use;
FIG. 9 is a perspective view thereof, shown in a second environment of use; and,
FIG. 10 is a perspective view thereof, shown in a third environment of use.
The broken lines depict environmental subject matter only and form no part of the claimed design.
